TROPHY

William D. Maloney, Redondo Beach, Calif., assignor to TRW Inc., Redondo Beach, Calif., a corporation of Ohio

Filed Mar. 6, 1967, Ser. No. 6,091

Term of patent 7 years

(Cl. D29—28)

FIGURES 2, 3 and 4 are slightly enlarged over FIGURES 1 and 5.

I claim:

The ornamental design for a trophy, substantially as shown and described.
